UNITED STATES PATENT OFFICE.

ELMER D. SMYSER, OF FELLOWS, CALIFORNIA, ASSIGNOR OF ONE-THIRD TO ROY M. SMITH AND ONE-THIRD TO PERL E. WILLIAMS, BOTH OF FELLOWS, CALIFORNIA.

TUBING BLEEDER.

Application filed March 1, 1926. Serial No. 91,632.

This invention relates to certain new and useful improvements in tubing bleeders for oil wells and the like, and has particular reference to improvements in tubing bleeders of the type set forth in my co-pending applications, Serial Number 19,744, filed March 31, 1925, and Serial Number 36,733, filed June 12, 1925.

In my last above mentioned co-pending application, I provided means operable upon turning of the well tubing for releasing the bleeder valve and embodying an element restrained from rotation with the well tubing by means of outwardly bowed leaf springs, having a tight or very effective frictional engagement with the inner surface of the well casing. While this construction is quite efficient, the same is objectionable to a certain extent by reason of the fact that the leaf springs, after continuous use, become so worn by their effective frictional engagement with the well casing, that renewal of the same is necessary at undesirably frequent intervals.

It is accordingly the primary object of the present invention to provide means whereby the leaf springs may be constructed to only have slight frictional engagement with the well casing to thereby minimize wear upon the same in the use of the device, and means whereby the before mentioned element of the valve releasing means is restrained from rotation in a more positive manner.

A further object of the invention is to generally simplify and improve tubing bleeders of the above character whereby the same will be more compact and durable in construction as well as more effective in operation.

Other objects will become apparent as the nature of the invention is better understood, and the same consists in the novel form, combination and arrangement of parts hereinafter more fully described, shown in the accompanying drawings, and claimed.

In the drawings, wherein like reference characters indicate corresponding parts throughout the several views.

Figure 1 is a fragmentary elevational view, of a well tubing equipped with a bleeder constructed in accordance with the present invention, the tubing and bleeder being illustrated in operative position

within a well casing shown in central longitudinal section; 55

Figure 2 is a fragmentary elevational view showing parts of the well tubing and bleeder shown in Figure 1 and drawn on a larger scale, the well tubing being in an elevated position preparatory to turning the same for effecting unseating of the bleeder valve;

Figure 3 is an enlarged fragmentary view of the well tubing, partly in elevation and partly in central vertical section, and illustrating the bleeder valve and adjacent parts; 65

Figure 4 is a transverse section taken upon line 4—4 of Figure 1, but when the leaf springs are shifted relative to each other so that the locking plate or dog plate is shifted toward locking or casing-engaging position; 70

Figure 5 is an enlarged transverse sectional view illustrating the manner of attaching the locking plate or dog to its supporting leaf spring; and 75

Figure 6 is an enlarged longitudinal section taken upon line 6—6 of Figure 2 to disclose the construction of the bleeder valve. 80

Referring more in detail to the drawings, 5 indicates the lower section of a well or pump tubing which is arranged within the well casing 6 in the usual way, the tubing 5 being of considerably lesser size than the pump casing 6 and disposed concentrically within the latter so as to leave a cylindrical space between the tubing and casing as clearly shown in Figure 4.

The lower tubing section 5 is formed with an opening in the side thereof, and the wall of this opening is preferably thickened to provide an outwardly projecting annular rib or flange 7 which acts as a reinforcement. A tubular plug or seat member 8 is removably threaded into the opening of the tubing section 5 and is closed at its outer end by means of a head or bleeder valve member 9 which is held in place to close the opening of the seat member 8 by a fragile means or connection as indicated at 11 so that leaking is prevented under normal conditions but whereby the bleeder valve 9 may be forcibly dislodged or detached from the seat member 8 when it is desired to drain the fluid from the pump tubing 5 above the bleeder valve opening. The seat member 8 and the valve member 9 are pref- 95 100 105

erably integrally formed and an external annular groove provided so as to reduce the thickness of the seat member at the point of connection of the latter with the valve member 9 whereby the fragile connection 11 is formed. The seat member 8 is preferably provided with an external continuous flange as at 12 inwardly of the valve member 9 arranged to abut the flange 7 for limiting 10 threading of the seat member into the opening of the tubing section 5 so that the valve member 9 is properly positioned externally of the tubing section 5 for being engaged by a striking member as will presently become 15 apparent.

The pump tubing 5 is formed with an external annular enlargement above the bleeder opening as clearly shown in Figure 3, and this enlargement is externally threaded as 20 indicated at 13. Adjustably threaded upon the enlargement is a sleeve 14 whose lower end portion is enlarged or flared as at 15 to form a striking member adapted to be brought forcibly downwardly into engagement 25 with the valve member 9 so as to release the latter by destruction of the fragile means or connection 11. It is thus apparent that when the sleeve 14 is held from rotation, and the tubing section 5 rotated, said 30 sleeve 14 will be caused to move downwardly so as to bring the enlargement 15 into engagement with the valve member 9 and thereby cause the latter to be displaced from the seat member 8 so that the opening in the 35 latter will be opened for allowing the fluid to pass out of the pump tubing 5 into the portion of the well casing 6 disposed therebelow.

A pair of collars 16 and 17 are rotatably 40 and slidably disposed upon the pump tubing 5 above the bleeder plug and in spaced relation to each other as shown clearly in Figure 1, which collars 16 and 17 are connected by a pair of diametrically opposed 45 longitudinally extending resilient strips or leaf springs 18 which are normally outwardly bowed for frictional engagement with the inner surface of the well casing 6. A further pair of collars 19 and 20 are rotatably and slidably disposed upon the pump tubing 5 between and respectively adjacent the collars 16 and 17, and these collars 19 and 20 are also connected by a pair of diametrically opposed longitudinally extending 55 resilient strips or leaf springs 21 which are normally outwardly bowed for frictional engagement with the inner surface of the well casing. The lower sleeve 17 is provided with a rigid depending arm 22, and the 60 threaded sleeve 14 is provided with an outwardly projecting lug 23 as shown clearly in Figures 1 and 2. The arm 22 is of such length as to normally have its lower end spaced above the lug 23 as shown in Figure 65 1, but when the tubing 5 is elevated until

the threaded sleeve 14 engages the sliding sleeve 17 as shown in Figure 2, the lug 23 will be disposed to engage the arm 22. In other words, when the pump tubing 5 is thus elevated, turning of said tubing will effect movement of the lug 23 into engagement with the arm 22 as shown in Figure 2. Loosely attached to the intermediate portion of one of the leaf springs 18 as by bolting or the like as indicated clearly at 24 in Figure 5, is a locking plate or dog 25 which projects laterally beyond one side of the associated spring 18 and towards the tangentially disposed and inwardly offset intermediate portion of one of the leaf springs 21 carried by the collars 19 and 20. The tangentially disposed and inwardly offset portion of the leaf spring 21, which is indicated at 26, is preferably formed by suitably twisting and bending such leaf spring, and it forms a cam element onto the outer surface of which the locking plate 25 is adapted to ride when the tubing section 5 is turned so that the locking plate or dog 25 is forced outwardly into gripping engagement with inner surface of the well casing 6 for locking the springs 18, collars 16 and 17 and arm 22 against further turning movement relative to the well casing. The threaded sleeve 14 preferably frictionally engages the tubing section 5 so as to be turned by the latter until the locking plate 25 firmly engages the well casing 6, whereupon the tubing section 5 may rotate in and relative to the sleeve 14 and collars 16 and 17 for allowing the latter and the arm 22 carried thereby to remain stationary under the action of the locking plate 25. On the other hand, the collars 19 and 20 are preferably loosely disposed on the tubing section 5 so that the slight frictional engagement of the springs 21 with the well casing 6 will prevent turning of the collars 19 and 20 with the tubing section 5 and thereby permit the locking plate 25 to ride in between the offset portion 26 and the well casing 6 as indicated in Figure 4. It will thus be seen that the frictional engagement with the well casing 6 is sufficient to maintain the collars 16 and 17 and 19 and 20, together with the parts carried thereby, spaced from and positioned above the sleeve 14 as shown in Figure 1 when the well tubing is lowered into the well casing 6. In other words, the springs 18 and 21 are not solely relied upon to restrain the arm 22 against rotation with the tubing section 5, but, on the contrary, the locking plate 25 serves this function so that, by reason of the slight frictional engagement of the springs with the well casing 6, wear of said springs will be minimized.

Assuming that the tubing has been lowered into the well casing and that the parts are in their positions as illustrated in Figure 1, the bleeder valve 9 may be unseated for

bleeding the tubing 5 by first elevating the latter until the threaded sleeve 14 engages the collar 17, whereupon the tubing is rotated until the lug 23 is brought into engagement with the arm 22 as shown in Figure 2. Upon continued turning of the well tubing the collars 16 and 17 and the attached springs 18 are caused to turn until the locking plate 25 rides onto the offset portion 26 of the adjacent spring 21 and is forced into locking engagement with the inner surface of the well casing 6. The collars 16 and 17 are then positively restrained from further rotation so that the arm 22 is maintained stationary for holding the threaded sleeve 14 against turning whereby, upon continued turning of the well tubing, there is a relative longitudinal displacement caused between the threaded sleeve 14 and the tubing section 5 so as to cause the lower end of the striking member or flared lower portion 15 of the sleeve 14 to be brought into engagement with the valve 9 and thereby cause the latter to be dislodged by destruction of the fragile means or connection 11. As soon as the valve 9 is displaced, the fluid will pass outwardly through the opening in the seat member 8 and will be drained from the pump tubing.

The pump tubing 5 is provided with an enlargement or lug 27 directly below the bleeder valve, and this lug forms an external stop which is engaged by the lower end of the flared sleeve portion or striking member 15 for preventing the threaded sleeve 14 from being threaded entirely off of the enlargement 13 after causing displacement of the bleeder valve 9.

While the locking device embodying the plate 25 and the offset element 26 has been herein disclosed as especially servicable in connection with tubing bleeders and particularly with tubing bleeders of the type herein disclosed, it is nevertheless to be understood that the invention, in so far as this locking feature is concerned, is not limited to tubing bleeders, the locking device being equally as well adaptable for use upon other devices where the same may be of service, such as upon swabs, packers and numerous other devices.

From the foregoing description, it is believed that the construction and operation as well as the advantages of the present invention will be readily understood and appreciated by those skilled in the art.

Minor changes may be made without departing from the spirit and scope of the invention as claimed.

60 What I claim as new is:—

1. A tubing bleeder for wells including a tubing section having a side opening, a bleeder valve closing said opening, fragile means retaining said valve in closed position, a member engageable with the valve

and displaceable relative to the tubing section for displacing the valve against the action of said fragile means, and means for displacing said member, said member displacing means including a sleeve threaded on the tubing section and operatively associated with said displaceable member, an outwardly projecting lug on said threaded sleeve, a pair of relatively rotatable frames rotatably and slidably mounted on the tubing section above the bleeder valve and adapted for frictional engagement with the inner surface of a well casing whereby the frames are elevated from the bleeder valve when the tubing section is lowered into the well casing and one of the frames is held against rotation when the tubing section is rotated, means operable upon turning of the other frame relative to said one frame to lock said other frame against continued turning with the tubing section relative to the well casing, and an arm rigid with said other frame and disposed to engage the lug on the threaded sleeve when the tubing section is elevated whereby turning of the tubing section will effect turning of said other frame until locked and will then effect movement of the threaded sleeve on the tubing section and displacement of the displaceable member and the valve.

2. In combination, a tubing section, a pair of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing.

3. In combination, a tubing section, a pair of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing, said last named means embodying a sleeve threaded on the tubing section and having a rigid outwardly projecting lug thereon, and an arm rigid with said other frame and disposed to engage the lug on the threaded sleeve when the tubing section is elevated.

4. In combination, a tubing section, a pair

of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing, said frames embodying pairs of collars rotatably and slidably mounted on the tubing section and respectively connected by longitudinally extending outwardly bowed leaf springs, and said locking means embodying elements associated with certain of said springs.

5. In combination, a tubing section, a pair of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing, said frames embodying pairs of collars rotatably and slidably mounted on the tubing section and respectively connected by longitudinally extending outwardly bowed leaf springs, and said locking means embodying elements associated with certain of said springs, the collars of one frame being disposed between the collars of the other frame.

6. In combination, a tubing section, a pair of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing, said frames embodying pairs of collars rotatably and slidably mounted on the tubing section and respectively connected by longitudinally extending outwardly bowed leaf springs, and said locking means embodying elements associated with certain of said springs, said locking elements embodying a locking plate loosely attached to a spring of one frame and an inwardly offset and tangentially disposed intermediate por-

tion of a spring of the other frame onto which the locking plate is adapted to ride for being forced outwardly into engagement with the well casing.

6. In combination, a tubing section, a pair of relatively rotatable frames rotatably and slidably mounted on the tubing section and adapted for frictional engagement with the inner surface of a well casing whereby one of the frames is held against rotation when the tubing section is rotated, non-positive means for causing the other frame to rotate with the tubing section when the latter is rotated, means operable upon turning of said other frame relative to said one frame to lock said other frame against continued turning with the tubing section relative to the well casing, said frames embodying pairs of collars rotatably and slidably mounted on the tubing section and respectively connected by longitudinally extending outwardly bowed leaf springs, and said locking means embodying elements associated with certain of said springs, the collars of one frame being disposed between the collars of the other frame.

7. In a tubing bleeder for wells, a tubing section having an opening, a bleeder valve element closing said opening, fragile means retaining said valve element in closed position, and means operable upon turning of the tubing section for releasing said valve element by destruction of said fragile means, said last named means embodying a sleeve threaded on the tubing section and having an enlarged end portion free from contact with the tubing, movable into engagement with the valve for releasing or displacing the latter.

In testimony whereof I affix my signature.

ELMER D. SMYSER
